UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

PAPER SHEATHING.

Application filed November 19, 1923. Serial No. 675,612.

My invention relates to improvements in paper sheathing adapted to be applied to the walls of frame buildings as a backing for stucco or the like; and one of the objects of the invention is the provision of furring units attached to the paper and adapted to receive and support the stucco composition and wire reinforcement therefor.

With the foregoing and other objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a face view of a section of my improved paper sheathing, and a section of wire reinforcement disposed thereagainst;

Figure 2 is an enlarged face view of a fragmental section of the paper sheathing;

Figure 3 is a perspective view of one of the wire-supporting members forming a portion of one of the furring units;

Figure 4 is a rear view of a fragmental section of the paper sheathing, showing the preferred method of attaching the furring units to the paper;

Figure 5 is a further enlarged longitudinal sectional view on line 5'-5', Fig. 2;

Figure 6 is a view similar to the view shown in Fig. 5, but with the clinching lips in their first step of formation;

Figure 7 is a face view of a section of the paper sheathing in a modified form to the extent that there is provided a locking plate at the rear side of the paper, which is adapted to be engaged by the clinching lips of the furring units;

Figure 8 is a rear view of a section of the paper sheathing in its modified form; and

Figure 9 is a sectional view of the modification on line 9'-9', Fig. 7.

Referring to the drawings in detail, throughout which like reference characters designate like parts:

The numeral 1 designates a section of my improved paper sheathing, which comprises a sheet of paper 2 provided with metal furring units 3, and adapted to be disposed across the face of studs 4 forming portions of the frame-work of the wall of a frame building

adapted to receive a coating of stucco composition.

The paper 2 may be of any suitable texture and thickness, preferably impregnated with bitumen pitch or like preservative to make it as nearly as practicable impervious to water to prevent exterior moisture penetrating to the wood-work of the wall.

The furring units 3, which are disposed at intervals across the face of the paper, are formed of sheet metal and comprises each a pair of laterally spaced apart outwardly bowed wire-supporting members 5, each of which embodying an intermediate member 6 having at its lower edge a base flange 7 adapted to seat against the paper 2, and at its upper edge a crown flange 8.

The wire-supporting members 5 are disposed with their concaved sides facing each other, thereby forming between them a kind of circular enclosure, and are secured to the paper by means of clinching lips 9, which are formed by striking or pressing forwardly through the paper intermediate portions of the flanges 7 and bending same back against the rear side of the paper (see Fig. 4).

The furring units are intended to be factory-built onto the paper, and in order to facilitate their application thereagainst it is preferable to form the clinching lips 9 after the disposition of the units thereon, and when cutting the metal for forming them to also cut the paper and double same back upon itself with the bending over of the lips (see Figs. 5 and 6). The operation for forming and clinching the lips 9 resulting in openings 10 being formed extending through both the flanges 7 and paper 2.

In the modified form of the invention as shown in Figs. 7, 8 and 9, there is provided a reinforcing plate 11, which comprises a thin rectangular sheet of metal disposed against the rear side of the paper directly in back of each furring unit and is adapted to provide reinforcement for this portion of the paper.

In attaching the furring units to the paper in this form of the invention, the lips 9 are formed by pressing forwardly a portion of the metal forming the flanges 7 through both the paper and the reinforcing plates and the whole then doubled back against the latter (see Figs. 8 and 9).

The paper sheets 2, fragmental sections of which only being shown in the drawings, may be of any desired widths and lengths, how-

ever, I have found in practice that a sheet having a width of about three feet and a length of about seventy-five feet when rolled up makes a bundle very convenient to handle in transportation as well as in applying it to the wall of a building.

Any number of the sheets may be used jointly in covering a section of a wall.

While the furring units may be disposed and spaced any desired distances apart on the paper, I prefer to dispose them in rows extending vertically across the paper, with a plurality of equally spaced units in each row, the rows spaced eight inches apart laterally, measured from center to center. Which eight inch lateral spacing of the rows permits, on account of the universal sixteen inch spacing of the studs of frame buildings, of the furring units of every second one of said rows to be disposed directly in front of one of the studs and the units forming the alternate rows to be disposed centrally between the studs. This arrangement of disposing one division of the furring units across the face of the studs permits of fastening staples 14 for securing the netting, being driven therewith through the units, while the other division of the units, which act initially as means for holding the netting a proper distance away from the paper, become permanently united to the netting by the hardening of the plastic material after the same is applied to the wall.

The primary object of providing two spaced apart coating wire-supporting members for each furring unit is to provide a driving area for the fastening staple 14 in which any excessive driving of the staple will result in merely deflecting the netting between said members, whereas, if the staples were driven along one side of a single furring member, it might cause the netting to become deflected out of its plane intermediate the furring units, resulting in inferior reinforcement for the plastic composition.

The objects of the base flanges 7 are to provide proper footing for the intermediate members 6 as well as to provide stock for the formation of the clinching lips 9; and the objects of the crown flanges 8 are to provide bearing for the wire netting other than would be provided by the comparatively narrow edges of the members 6 were the flanges omitted, and also to provide lateral projections, particularly for the units without stud supports, around and back of which the plastic material may be spread for forming a "key" for permanently holding the netting and plaster to the paper.

The employment of the reinforcing plates 11 is optional, their use, however, prevents any accidental tearing of the paper by the clinching lips when the sheathing is subjected to unusually rough handling.

It is to be understood that my improved

sheathing may, if desired, be applied to the siding boards sometimes applied to the studs of plastered structures, instead of applying it to the studs direct. If applied to the siding boards, a fastening staple may be provided for each furring unit.

I claim:

1. In means of the character described, a wire-supporting member comprising an intermediate member having one edge bent to one side to form a base flange, and its opposite edge bent over to the same side to form a crown flange, said wire-supporting member adapted to seat against one side of a sheet of paper, and means formed integral with said wire supporting member projecting through said paper and overlying the opposite side thereof for binding said paper against said wire supporting member.

2. The combination with a sheet of paper, of a wire-supporting member seated against the face side thereof, a portion of said paper struck rearwardly and doubled against the body portion thereof, thereby forming an opening therethrough, a clinching lip on said wire-supporting member projecting through said opening and bent against said first named portion of the paper for binding it and the body portion of the paper firmly between said clinching lip and said wire-supporting member.

3. In means of the character described, a sheet of paper, and a furring unit formed of sheet metal and comprising a pair of laterally opposed oppositely bowed wire-supporting members, and means for permanently attaching said members to said paper independently of each other.

4. In means of the character described, a furring unit having a wire-supporting member provided with clinching lips adapted for securing it permanently to a sheet of paper, said member longitudinally arched in a plane extending parallel with said paper.

5. In means of the character described, a sheet of paper, a wire-supporting member seated against one side of said sheet and projecting substantially at right angles outwardly therefrom, clinching lips integrally connected to said member projecting through said paper and bent over against the opposite side thereof, whereby said paper is engaged by said member and said lips and firmly locked therebetween thereby.

6. In means of the character described, a strip of flat metal disposed against one side of a stucco backing, and a strip of metal having a flat portion disposed against the other side thereof and having a lath spacing portion projecting at an angle thereto, one of said strips having a projection projecting through both said backing and said other strip and overlying a portion of the latter for binding said backing between said strips.

7. In means of the character described, in

- combination, a sheet of paper, a reinforcing element disposed against one side of said paper, and a furring element disposed against the opposite side of said paper carrying a 5 lath spacing element projecting therefrom, one of said elements provided with a projection projecting through said paper and engaging the other one of said elements for connecting said paper and elements together.
- 10 8. A stucco backing adapted to lie back of metal lath and comprising, in combination,
- a sheet of paper, and a plurality of furring units attached thereto each unit comprising a base portion having means for securing the same to said sheet of paper and an outstanding portion adapted to engage metal lath and support the same in spaced relation thereto.
- In testimony of the foregoing being my own, I have hereunto affixed my signature this 12th day of November, 1923.

GEORGE F. VOIGHT.
